UNITED STATES PATENT OFFICE.

WILLIAM BUCK WALTON, OF HALIFAX, ENGLAND.

DRAWING OR DRAFTING MECHANISM FOR DRAWING OR DRAFTING COTTON AND OTHER FIBROUS MATERIAL.

Application filed February 11, 1926, Serial No. 87,725, and in Great Britain May 2, 1925.

This invention relates to self weighted top rollers of light weight employed in the drafting system of ring spinning and other textile machines having similar drawing rollers in which adjacent top rollers are flexibly connected to an intermediate or central boss to prevent lagging or stoppage of the rollers.

According to this invention I connect two or more of the rollers by means of a non-rigid coupling such as flexible cords, chains, cables, wires, links, springs or the like passed through the centre or attached to the ends or journals of the rollers.

The invention will be fully described with reference to the accompanying drawings.

Figs. 1 and 2 are longitudinal sectional plan and transverse sections of two rollers, connected together by a flexible cord.

Fig. 3 is a longitudinal sectional plan showing a line of rollers.

Figs. 4 and 5 are similar views to Figs. 1 and 2 of a modification.

Figs. 6 and 7 are similar views of a further modification.

Figs. 8 and 9 are similar views of a further modification.

Figs. 10 and 11 are similar views of a further modification.

Figs. 12 and 13 are similar views showing a weighted roller connected to two light rollers.

Figs. 14 and 15 are similar views showing a modification of same.

Figs. 16 and 17 are similar views showing a further modification of same.

Fig. 18 is a transverse section of the saddle showing the roller in working position.

Fig. 19 is a similar view with the roller in position for cleaning.

Fig. 20 is a front view of Fig. 18.

Fig. 21 is a plan of same.

Fig. 22 is a side elevation of the loose saddle.

Fig. 23 is a plan of a further modification.

Fig. 24 is a transverse section of same.

The roller A may be of any suitable construction of self weighted roller and may be either uncovered or covered with leather or the like in customary manner.

In the forms shown in Figs. 1 to 5 the rollers are of the ordinary size and length to fit between the cap bars of the roller stands (not shown) and are connected by a cord, or cable B, wire B² or the like inserted in a longitudinal bore a drilled or formed

through the centre of the roller secured within the rollers so as to rotate with them but allow of a slight degree of relatively independent movement. Two, three or any number of rollers may be coupled together though in use two will probably be found most convenient. Should the rotation of one of the rollers A be stopped the other roller will continue to rotate until the twist or slack of the non-rigid coupling B or B² is taken up and then impart its movement to the first roller.

In the form shown in Figs. 12 to 17 and Figs. 23 and 24 each light roller is divided into two parts A¹ A² with a heavy or weighted roller D between the two light rollers A¹ A² to rest directly in contact with the bottom fluted roller and receive rotation therefrom. The two short or part rollers A¹ A² are connected to the roller D, by a flexible cord B or other non-rigid coupling B³ inserted in a longitudinal bore d in the heavy roller D and in a longitudinal bore a¹ a² in the light rollers A¹ A².

In the form shown in Figs. 6 to 11 the rollers A³, A⁴ are of similar construction and connected together by non-rigid link or hook couplings B³ (Figs. 10 and 11) or flat twisted tape B⁴ (Figs. 6 and 7) or a square rubber bar B⁵ (Figs. 8 and 9) affixed to the ends of the rollers so that the continued rotation of one will prevent the stoppage of the other.

A thin tube of tin or other material may surround the flexible cord, chain, cable or wire to prevent collection of fluff or fly thereon, and the central weighted roller D may be either plain, fluted or covered with leather.

In the forms shown in Figs. 12, 13 and 18 to 21 the heavy or weighted intermediate roller may be retained in position by a combined saddle and cap neb e¹ the saddle e resting on the neck of the front top roller F and the cap neb e¹ resting on the journals of the roller D a weight being applied by a weight hook G. The cap neb e¹ may be adjustable in relation to the saddle e the two parts being secured by a screw or bolt. The bearings on the cap neb e¹ are such as to engage and bear upon the journals of the roller D only and apply no weight whatever to the adjacent light rollers A¹, A². In the case of a front top roller with loose bosses f on a non-rotary spindle f¹ the saddle and cap neb e¹ may be attached to the spindle by soldering,

bronzing, set screws or other means and the roller D may be retained in the cap neb e¹ by springs e² so that it may turn over for cleaning (see Fig. 19). By this construction the amount of frictional contact between the weighted roller D and the bottom fluted roller can be regulated and each set of light rollers maintained in continuous alignment while each light roller A¹ is allowed to move independently of the other to and from the bottom fluted roller as the rove or sliver passes between. The design of the saddle and cap neb may vary according to the construction of the front top roller and the light rollers employed.

In the form shown in Figs. 23 and 24 the heavy or weighted intermediate roller D is retained in position by a combined saddle and cap neb e³ the saddle e² resting on a bar or rod H running the full length of the machine and carried by the frame and the cap neb e³ resting on the journals of the roller D.

The saddle e² is formed with a slot e⁴ through which a set screw e⁵ is screwed into the rod H a spring e⁶ on the screw applying pressure to the saddle e². The rod H may be provided with a backing h against which the saddle e² bears.

This arrangement can be employed where the fitting of the saddle on the front roller is inconvenient or unsuitable.

What I claim as my invention and desire to protect by Letters Patent is:—

1. Self weighted top rollers for ring spinning and other machines comprising a plurality of rollers, a flexible non-rigid coupling connecting adjacent rollers together to allow adjacent rollers to move out of true alignment and to have a certain limited amount of rotary motion with respect to each other as required by the fibres passing under them.

2. Self weighted top rollers for ring spinning and other machines comprising a plurality of rollers, a flexible non-rigid coupling inserted in a bore in the rollers by which adjacent rollers are connected together to

allow adjacent rollers to move out of true alignment and to have a certain limited amount of rotary motion with respect to each other as required by the fibres passing under them.

3. A self weighted top roller for ring spinning and other machines constructed with a bore in the interior a flexible non-rigid coupling inserted into and extending at the ends of said roller by which the roller is connected to adjacent rollers to allow each end of the roller to move out of alignment to a different extent with adjacent rollers and also to have a certain limited amount of rotary motion with respect to that of the adjacent rollers as required by the fibres passing under it the roller and adjacent rollers being driven through the flexible non-rigid couplings.

4. Self weighted top rollers for ring spinning and other machines comprising a plurality of rollers, a cord connecting adjacent rollers together inserted in a bore in the rollers means for affixing the cord to each roller to allow adjacent rollers to move out of true alignment and to have a certain limited amount of rotary motion with respect to each other as required by the fibres passing under them.

5. A self weighted top roller for ring spinning and other machines constructed with a bore in the interior, a cord inserted into the bore and extending at the ends of said roller by which the roller is connected to adjacent rollers to allow each end of the roller to move out of alignment to a different extent with adjacent rollers and also to have a certain amount of rotary motion with respect to that of the adjacent rollers as required by the fibres passing under it, and means for connecting the cord at a single central point to the roller, whereby the roller is driven on the rotation of the cord.

In testimony whereof I have hereunto set my hand.

WILLIAM BUCK WALTON.
